JOHN T. McCOURT, OF LOS ANGELES, CALIFORNIA

SMELTING FURNACE

Application filed June 10, 1926. Serial No. 115,054.

This invention relates to and has for a main object the provision of an improved method and means for smelting ore, and more particularly iron ore, which is generally the more difficult to reduce in a smelting process.

Another object is to provide a method and means for smelting ore and arranged to burn a CO gas in the presence of the ore to be reduced, preferably by introducing a hydro-carbon fuel with a proper mixture of air from the atmosphere into the combustion chamber or zone of the crucible in the presence of the ore, in such a manner that oxidation of the ore will be prevented, thus eliminating the necessity for the use of other carbonaceous substances such as coke, which is ordinarily used in the reduction of iron ore.

Another object is to provide a process and means for reducing ore which includes the burning of carbon in suspension, and the disposition of the ore in the crucible in such a manner that the reduction of the ore in the presence of the burning carbon will be more quickly effected than in other processes where a substance such as coke is used under the obtaining methods, together with a method and means for effecting a complete regeneration of the gases constituting the products of combustion, such as carbon monoxide (CO) and carbon dioxide (CO₂) and hydrogen (H).

Another object is to provide a method of the character mentioned which consists in introducing preheated or roasted ore into a crucible, preferably disposed at an angle inclined from a horizontal line, introducing a liquid fuel such as hydro-carbon fuel into the crucible, and burning the carbon in the presence of the ore, accumulating the molten metal and slag resulting from the fusing of the ore, in a hearth, separately drawing off the slag and the metal, and drawing off the products of combustion from the crucible into a regenerator.

A further object is to provide improved means for introducing the hydro-carbon fuel into the crucible and the hearth, whereby a maximum temperature may be obtained, together with means for regulating the vol-

ume of the fuel introduced to the combustion chamber from points externally of the crucible, and the corresponding regulation of the heat produced therein.

A further object is to provide a method and means for reducing ore, which consists in initially heating the ore to a point substantially below fusing temperature, charging an inclined crucible with the preheated ore at regular intervals, or continuously, heating the crucible and a hearth connected therewith simultaneously to a uniform temperature effective for reducing the ore to a molten state, and separately drawing off the products of combustion, the molten metal and the slag, in a continuous operation.

A still further object is to provide a smelter particularly adapted for the reduction of iron ore to a molten state, which includes a hearth for receiving and holding the molten metal and slag after the reduction of the ore, a crucible inclined upwardly from the hearth and arranged to receive the ore at regular intervals, or continuously, a roaster or preheating device for initially receiving the ore and so arranged in relation to the crucible that the ore may be transferred after the preheating operation to the crucible for complete reduction, a regenerator adapted to receive the products of combustion, and means for introducing the combustible elements into the regenerator.

Still other objects will appear as the description of my invention progresses.

In the accompanying drawings I have shown a preferred embodiment of my invention, subject to modification within the scope of the appended claims without departing from the spirit thereof, in which:

Fig. 1 is an elevation, on a reduced scale with certain details omitted, of my improved furnace for smelting ore.

Fig. 2 is a side elevation of the same in detail, with the roasting mechanism omitted.

Fig. 3 is a top plan view of the same.

Fig. 4 is an end view thereof.

Fig. 5 is a sectional elevation of the apparatus shown in Fig. 2.

Fig. 6 is a sectional elevation on line 6—6 of Fig. 5.

Fig. 7 is a sectional elevation on line 7—7 of Fig. 3.

Fig. 8 is an enlarged side elevation of one of the burners for introducing a hydro-carbon fuel to the combustion chamber.

Fig. 9 is a side elevation of the same in connection with the hearth, showing the water cooled combustion block, which is also typical of the construction of the crucible.

Fig. 10 is a sectional elevation of the burners adapted to burn a liquid hydro-carbon fuel.

Fig. 11 is an enlarged sectional view of the burner proper; and

Fig. 12 is a sectional plan of the same on line 12—12 of Fig. 11.

Briefly described, my improved method and means includes a roaster R, a hearth H, a crucible C, and a regenerator G, arranged preferably as shown in Fig. 1, with the hearth H, crucible C and regenerator G constructed as an integral unit. The crucible C is cylindrical and inclined at a substantial angle from hearth H to and in communication with the regenerator G, so that the ore will move by gravity to the hearth. The roaster R is mounted at a substantial elevation above the plane of the hearth H and crucible C, on a suitable frame F, and is adapted to be rotated during the operation of the mechanism by suitable means.

Referring to Fig. 1, the roaster is provided with a steel outer jacket, of cylindrical form, with a refractory lining 2 of fire-brick, or other substance, and is in the form of a substantially elongated cylinder with an inlet 3 through which the ore is supplied to the interior of the roaster by suitable means, and an outlet 5 at the opposite end through which the ore may be discharged after its passage through and at the completion of the preheating operation in the roaster.

The roaster is rotatably mounted on the frame F and is supported on a plurality of cradles 6, 6, which have anti-friction rollers 7, 7 mounted thereon, and adapted to rotatably engage bands 8, 8, attached to the periphery of the jacket. At substantially spaced points the jacket is provided with annular gears 9, 9, which are adapted to mesh with and be driven by pinions 10, 10 carried on an elongated driving shaft 11 which is journaled in brackets 12, 13 and 14 attached to the top of the frame F. The shaft 11 may be rotated by a gear or pulley 15 at one end thereof, and the roaster R is disposed at an angle and is inclined downwardly from the inlet 3 to the outlet 5, so that the ore introduced through inlet 3 during the preheating operation will be gradually moved in the direction of the outlet 5 for delivery to the crucible C, as hereinafter described.

The discharge end of the roaster R is provided with an orifice in the end 17 thereof, adjacent which a gas or liquid fuel burner

B is mounted, whereby the internal chamber of the roaster may be heated to a proper temperature in the roasting process.

The roaster R, as shown in Fig. 1, is disposed above and in near proximity to a pair or more of hoppers 18 and 19 which are mounted on the inclined upper surface of the crucible C, and are in communication with the combustion chamber 20 therein, in order that the ore from the roaster R may be discharged intermittently or continuously into one or both of the hoppers 18 and 19 by suitable means (not shown) and thence into the chamber 20 of the crucible C.

It will be noted by reference to Fig. 5 that the crucible C is inclined at an angle of approximately thirty degrees, but the angle thereof may be changed to suit varying conditions.

Said crucible has an outer casing 21 of steel or iron, and an inner lining 22 of refractory substance, such as fire-brick, and is of cylindrical cross section and substantially elongated. At its lower end the crucible C is in direct communication with the hearth H, and said hearth has a metallic water jacket 23 arranged therearound in sections of suitable size, an intermediate wall of brick as at 24, and an inner lining 25 of refractory substance such as fire-brick. Said hearth also has a floor 26 of refractory material which is suitably constructed on a base 27 of concrete or other substance.

At a point slightly above the opening 28, which affords communication between the crucible and the hearth, the floor of the crucible C is provided with a slight internal enlargement 29, which may be as shown or suitably grooved for the purpose of retarding the movement of the ore from the inclined surface of the crucible into the hearth, and providing a shallow trough for the reception of the molten metal, as more fully described hereafter. Also, the upper wall of the crucible almost opposite the enlargement 29 is provided with a depending internal baffle 30 which serves to deflect the heat from the hearth downwardly at an incline into the crucible C, so as to provide a point of maximum heat in the crucible in the region adjacent the enlargement 29 and the baffle 30.

Adjacent the upper end of the crucible, I provide a regenerator G which is preferably of rectangular cross section, and is constructed of brick or other suitable substance, with a rear wall 31, front wall 32, side walls 33, 33, and a top 34, the rear wall 31 being provided with checkered brick work 35 at its junction with the crucible C so as to provide a plurality of openings 36, 36 affording communication between the chamber 20 of the crucible and the chamber 37 of the regenerator, for the purpose of drawing off the products of combustion from the crucible into the regenerator.

The crucible C is supported on a suitable frame F' of steel, and both the crucible and the hearth are braced transversely by means of rods 38, 38, etc., connected at their ends to steel beams 39, 39, etc., shown particularly in Figs. 3 and 4. It will be understood, however, that this type of reinforcement and the frame for supporting the crucible and hearth is immaterial to my invention and may be modified or omitted so as to meet varying conditions.

A plurality of openings as at 40 are provided in the walls of the regenerator R which are covered by doors 41, arranged in a suitable manner for sealing the openings 40 under normal pressure within the chamber 37, and which are adapted to open under abnormal pressures for relieving the pressures within the generator.

The crucible C and the hearth H are provided with a plurality of burners B arranged at staggered points on opposite sides thereof, all of said burners being connected with a steel pressure blower P, by means of a common pipe 42 or a series of such pipes, which extend from the blower P through the wall 32 of the regenerator, and thence upwardly through the chamber 37 of the regenerator and the top 34, with corresponding laterals 43 and 43' leading to the burners B, B, etc., on opposite sides of the crucible and the hearth, as shown in Fig. 4.

Liquid fuel is supplied to the burners B by means of one or more pipes 44 connected with a fuel pump P', which in turn is connected by means of a pipe 45 with a suitable tank as a T, for holding the fuel so that under a pressure of approximately one hundred pounds per square inch it may be delivered to the burners B for mixture with the air from the blower P which is preheated in the regenerator G.

As in other systems where liquid hydrocarbon fuels are used for burners of the character shown herein, the oil delivered from the pressure pump P' may preferably be preheated prior to the introduction of the oil to the burners B so as to afford a more perfect vaporization and combustion.

At a suitable point on the regenerator G, or adjacent thereto, I provide a forced draft blower as at b, the intake of which is connected by means of a pipe 46 with the regenerator so as to afford communication with the chamber 37 thereof. Said blower b is for the purpose of exhausting the products of combustion from the crucible C, through the regenerator G, and is preferably water-cooled for the purpose of handling gas with a temperature of approximately one thousand degrees Fahrenheit. The outlet of the blower b is connected with the burner B of the roaster by means of a pipe 48, so that the combustible gas exhausted from the chamber 37 of regenerator G may be delivered to the burner B of

the roaster through pipe 48 for heating the roaster to a proper temperature.

In the operation of my improved smelter as hereinbefore described, the ore is admitted through the inlet 3 to the roaster R while said roaster is being rotated by the means shown. An initial temperature is maintained by means of the burners B as the ore is moved from one end thereof to the other for discharge into the crucible. The crucible C is charged with the ore continuously or intermittently, as may be desired, by suitable means, and a proper charge of ore in the effective operation of the crucible will fill the crucible to the extent of about one-half of its area, providing a combustion chamber in the upper portion of the crucible above the body of ore in the lower portion thereof.

When the hearth H and the crucible C are initially heated to a temperature which will completely fuse the ore, and the crucible is charged with a sufficient quantity of the ore, a state of incandescence will prevail in the hearth and in the combustion chamber of the crucible above the body of ore. Thus ample space in the crucible is provided for expansion of the gases during combustion, and the heat created in the combustion chamber will be applied generously and directly to the body of ore so that as the ore is moved gradually down the inclined bottom of the crucible, it will gradually be reduced, and just above the point 29 in the crucible the molten metal will accumulate and flow over the enlargement 29, through the opening 28 into the hearth H, in the form of a metallic molten ore and slag, the iron being heavier than the slag settling to the bottom of the hearth H, and flowing off through an outlet O, over a trough t for further disposition, and the slag being the lighter of the two substances being discharged through an opening O' and a trough t', as in other cases, details of this structure being immaterial to my invention.

In this case it will be observed that by the arrangement of the burners shown, and the disposition of the same at frequent intervals on each side of the crucible C and hearth H, I may vary the temperature at local points within the crucible to meet necessary conditions of use, but a distinctive feature of my invention consists in the application of heat to the hearth wherein is maintained a body of the molten metal so that subsequent to the reduction of the ore there can be no cooling of the molten metal in the hearth, as is possible in other types of smelters.

It will be understood, furthermore, that the extraction of the molten metal from the ore is completely effected within the crucible and the hearth serves the purpose of accumulating the molten metal from which the same may be drawn for further disposition and use.

Now, I have found that a sufficient temperature for reducing ore, particularly iron

ore, to a molten state may be provided within the combustion zone of the crucible C and the hearth H by the employment of a liquid hydro-carbon fuel or a gas, preferably the former, and to this end I have devised for use 5 in connection with my smelter a burner embodying the characteristics shown in Figs. 10 to 14 inclusive, to which reference is now made.

10 Said burner includes a body 50, approximating in form the usual elbow pipe fitting, with a vertical neck 51 and a horizontal neck 52. The neck 51 is adapted to be connected with the pipe 43 or 43' from the blower P by 15 means of a fitting or more preferably a shut-off valve 54, interposed between the sections of the pipes 43 or 43', as the case may be, or adjacent the burners B so as to individualize the operation of the several burners.

20 The portion 52 of the burner has an outlet cap 55 which is removably attached to the body 50, as shown in Fig. 9, the outer end of said cap being tapered and projecting into an orifice 58 in the wall of the crucible or hearth, as at W preferably so as to form an air tight 25 connection. I provide in the wall, opposite each burner a combustion block 59, in which the opening 58 is formed conically with the smaller end adjacent the burner and the larger 30 end of the cone opening into the crucible or the hearth, as the case may be.

Within the body 50 I provide an elongated tube 60 which is threaded at 61 into a boss 62 in the rear wall 63 of said body. The 35 forward end of said tube is enlarged at 64 and is internally threaded to receive a burner tip 65, shown in Figs. 11 and 12 in detail. Outwardly of the burner body 50 I provide a connection between the tube 60 and the 40 fuel supply pipe 44, through which liquid fuel may be supplied to the chamber 60' of tube 60, outwardly of the pipe connection 44. The tube 60 is internally threaded at 66 to receive a correspondingly threaded 45 portion 67 on a valve stem 68, which extends throughout the length of the tube 60, and from the outer end of said tube 60, through a packing gland 69.

The end portion 70 of said stem is provided with a hand wheel 71 by means of 50 which the stem 68 may be advanced and retracted in the tube 60 for the purpose of regulating the flow of fuel through the burner tip 65. The burner tip 65 has a hexagonal 55 wrench receiving head 72, and a reduced externally threaded portion 73 which is threaded into the portion 64 of the tube 60, as shown in Fig. 10. The valve stem 68 has an enlarged head 69 which is reciprocably positioned in a central bore 74 of the burner 60, and a bore 75 is provided in member 65 in which the valve head 69 is slidably held. Said chamber is connected by means of inclined and tangentially disposed passages 76 65 and 77 and communicating passages 78 and

79 with the chamber 60' within the portion 64 of the tube 60.

By reference to Fig. 12 it will be noted that the passages 76 and 77 are tangentially disposed with respect to the axis of the burner 65 and the openings of passages 76 70 and 77 into and at different positions longitudinally of the chamber 75, so that a minute control of the flow of fuel into the chamber may be effected by the advance or 75 retraction of the stem 68 and head 69 within the member 65. In this connection it will be understood that I may use any number of the passages 76 and 77 arranged at different points and at suitable angles for 80 carrying out the objects of my invention.

The chamber 75 has an outlet 80 in communication with a conical depression 81 on the outside of the head 72, and said head is positioned within the cap 55 of the burner 85 and adjacent the opening 82 in said cap. Thus, the fuel under pressure admitted to the chamber 60' of tube 60, through pipe 44 is discharged through the passages 78 90 and 79, and thence through the passages 76 95 and/or 77 into the chamber 75, and thence through the outlet 80 into the conical inlet chamber 58 of the combustion block 59 of the hearth H or crucible C. The size of the 100 passages 78, 79, 76, 77 and 80 is such that the liquid fuel will be thoroughly atomized and the air from the pipes 43 and 43' is admitted to the presence of the atomized liquid fuel through the necks 51 and 52 of the burner body 50.

Now, it will be understood from the description of my smelter and the burners for heating the same to a proper temperature that I have provided an efficient means for reducing the ore by means of a hydro-carbon 105 fuel of either liquid or gaseous form, whereby carbon may be burned while in suspension, and for maintaining a proper temperature or range of temperatures within the hearth and the crucible for effectively reducing the ore to a molten metallic state, whereby the molten metallic substances may be withdrawn separately from the slag. Furthermore, I have provided a novel and efficient means of preventing the oxidation 110 of the ore during the smelting process, and means for utilization of the combustible products of combustion for preheating the ore preliminary to the reduction thereof.

In addition to these features, by the arrangement of the several elements shown and described, it will be understood that the interior of the furnace, including the hearth, crucible and regenerator is air tight and so arranged that all of the air admitted thereto is under complete control at all times during the operation thereof.

By the use of my smelter, as shown and described, I am enabled to reduce the iron ore to a molten metallic state by burning the 115

carbon in suspension to a CO with one-half of the air required to burn it to a CO₂. This effect I am able to produce by the minute control of the air to the combustion chambers of the hearth and crucible, and the result is a positive preventive against the oxidation of the ore. Of course, it will be understood in the charging of the crucible C with the preheated ore, I also introduce into the crucible a sufficient amount of a suitable flux, such as lime, as in other types of smelters, but the elements admitted to the combustion chambers of the furnace are such as to prevent an excess quantity of oxygen, insuring a carbon monoxide instead of a carbon dioxide condition in the combustion chambers.

The gas in the regenerator is composed of from twenty-five to forty per cent CO gas, the balance being CO₂, H and N. The gases introduced to the burners B of the roaster R is substantially of the same constituency as the gas in the regenerator.

My improved furnace or crucible is preferably cylindrical in cross section. The combustion chamber in the crucible occupies the upper half thereof, while the lower half is adapted to contain the iron ore and flux to be reduced. The application of fuel oil and air is made through twyers on the sides of the furnace, and the burners for handling fuel oil and air may be so positioned at suitable angles that they will discharge fuel and air into the upper part of the furnace so that at no time will the flame reach the body of ore and flux in the bottom of the furnace. The amount of fuel oil with which the burners are charged is necessarily in excess of the air necessary to complete proper combustion.

Due to this fact, a CO gas is produced, because of the non-oxidizing condition which is necessary to separate iron from its oxides.

After the ignition and burning of fuel oil in the crucible, an incandescent non-oxidizing reducing atmosphere prevails which, due to the cylindrical form of the furnace, causes the gases to follow the circular walls thereof, whereby they are conducted to the iron ore and flux which occupies the lower portion of the furnace. The attack of the gases on the ore and flux produces a molten mass of iron and slag which moves by gravity to the hearth below and accumulates in a sufficient quantity to be drawn off.

In this connection it is understood that the hearth is always kept at the same temperature as the crucible.

What I claim is:

1. A smelting furnace including a hearth and an inclined crucible connected therewith, a plurality of hydro-carbon burners connected with said hearth and said crucible for providing effective ore reduction temperatures therein, said crucible arranged to receive and hold a body of ore in the lower

portion thereof and provided with a combustion chamber in the upper portion thereof, and means within the crucible and above said hearth for deflecting the heat from the hearth against the body of ore whereby a maximum temperature may be provided at the point of junction between the hearth and crucible, for the purpose described.

2. A smelting furnace including a hearth and an inclined crucible connected therewith, a plurality of hydrocarbon burners connected with said hearth and said crucible for providing effective ore reduction temperatures therein, said crucible arranged to receive and hold a body of ore in the lower portion thereof, and provided with a combustion chamber in the upper portion thereof, means within the crucible and above said hearth for deflecting the heat from the hearth against the body of ore whereby a maximum temperature may be provided at the point of junction between the hearth and crucible, and means formed in the lower portion of said crucible for accumulating the molten metal at said point of maximum temperature for delivery to said hearth.

3. A smelting furnace including a hearth and an inclined crucible connected therewith, a plurality of hydro-carbon burners connected with said hearth and said crucible for providing effective ore reduction temperatures therein, said crucible arranged to receive and hold a body of ore in the lower portion thereof and provided with a combustion chamber in the upper portion thereof, means within the crucible and above said hearth for deflecting the heat from the hearth against the body of ore whereby a maximum temperature may be provided at the point of junction between the hearth and crucible, means formed in the lower portion of said crucible for accumulating the molten metal at said point of maximum temperature for delivery to said hearth, and means adjacent to and in communication with said crucible for receiving the products of combustion.

4. A smelting furnace including a hearth and an inclined crucible connected therewith, a plurality of hydro-carbon burners connected with said hearth and said crucible for providing effective ore reduction temperatures therein, said crucible arranged to receive and hold a body of ore in the lower portion thereof and provided with a combustion chamber in the upper portion thereof, and means formed in the lower portion of the crucible for the accumulation of the molten metal at a point of maximum temperature for delivery to said hearth.

5. A smelting furnace including a hearth and an inclined crucible connected therewith, a plurality of hydro-carbon burners connected with said hearth and said crucible for providing effective ore reduction temperatures therein, said crucible arranged to re-

ceive and hold a body of ore in the lower portion thereof and provided with a combustion chamber in the upper portion thereof, and means in the crucible for providing a maximum temperature at the point of junction between the hearth and crucible.

6. A smelting furnace including a hearth and an inclined crucible connected therewith, a plurality of hydro-carbon burners connected with said hearth and said crucible for providing effective ore reduction temperatures therein, said crucible arranged to receive and hold a body of ore in the lower portion thereof and provided with a combustion chamber in the upper portion thereof, means in the crucible for providing a maximum temperature at the point of junction between the hearth and crucible, and means for accumulating the molten metal in the crucible at said point of maximum temperature.
